ANTISKID DEVICE

Le Roy I. Dick, Cleveland, Ohio, assignor to The Cleveland Chain & Manufacturing Company, Garfield Heights, Ohio, a corporation of Ohio

Application December 6, 1933, Serial No. 701,171

11 Claims. (Cl. 152—14)

This invention, as indicated, relates to an anti-skid device of the type generally known as an emergency tire chain. More particularly, it comprises a device adapted to be placed upon an automobile tire with anti-skid members extending over the tread thereof and securing means extending over the felloe of the wheel and firmly holding the anti-skid device in place.

Devices of this character have heretofore been produced, but at times have been found to be subject to displacement due to the centrifugal force exerted on a heavier portion of the device so as to move such heavier portion outwardly and disturb the original adjustment of the anti-skid device relatively to the tread. In some instances, it has been sought to avoid the effects of centrifugal force upon a device of this character by making the clamp and buckle of nearly the same weight, whereby centrifugal force will not tend to advance either of them outwardly on the wheel to any material extent. There are disadvantages in attempting to make the buckle or means for fastening the free end of the strap to the supporting plate for the anti-skid device of equal weight to the clamping or fixed end of the strap for supporting the structure, inasmuch as the buckle involves more mechanical parts and these would have to be reduced beyond the limits of safety to make them of equal weight with the other end of the device, or the other end would have to be unduly thickened to bring the weight up to the desired weight of the buckle structure.

The present invention has in view therefore the idea of so securing the device to the tire that the same will be frictionally held and will resist all efforts of centrifugal force to dislodge the same irrespective of the fact that the buckle portion of the device may be of considerably greater weight than that of the clamping end of the device. This permits manufacturing of the device to be carried on in the normal manner wherein parts requiring strength or a greater number of pieces are considered solely as to their own strength requirements and not as to whether they must be made heavier or lighter to balance another part which scientifically considered should have no arbitrary or limiting effect in controlling the design, thus being free of the requirement of making the buckle portion of the device thinner or lighter than the clamping portion at the fixed end of the strap or of making the clamping portion of the device at the fixed end of the strap extra heavy to approximate the weight of the buckle. Each of these parts may be made of any

required design to fulfil the proper mechanical functions of the same and involve no alterations or increase or diminution of the parts for the purpose of properly centering the device upon the tire and maintaining it there.

The principal object of the present invention is to provide an anti-skid device of the type known as an emergency chain and having structural characteristics which tend to prevent side-slip thereof when applied to the tire.

Another object of the invention is to provide an anti-skid device for tires adapted to fit smoothly against the outer surface of the tire and adjacent parts and at the same time to frictionally engage the tire at points below the point of greatest transverse diameter in such manner as to prevent displacement of the device from its original position of adjustment.

Another object of the invention is to provide an anti-skid device having an improved type of strap securing and fastening means whereby easy engagement of the strap with the tire and wheel may be had and secure locking of the same may be obtained without injury to the long life of the structure.

Another object of the invention is to provide a device of the character set forth which will be adapted for quantity production and at the same time provide structural features which are superior to those of this type generally available to the public and which will remain free of mechanical difficulty irrespective of the length of time during which they may be in use.

Another object of the invention is to provide an improved securing device for an emergency tire chain which by its structure will have a double locking effect through the movement of one of the parts past dead center and yet adapted for release without unusual effort.

Another object of the invention is to provide means for securing an anti-skid device to a wheel in such manner that the greater the pull upon the device, the greater the gripping effect upon the free end of the securing member as well as the increase of snubbing action adapted for resisting strains of the greatest magnitude.

Other and further objects of the invention will appear in the course of the following description.

To the accomplishment of the foregoing and related ends, said invention, then, consists of the means hereinafter fully described and particularly pointed out in the claims, the annexed drawing and the following description setting forth in detail certain structures embodying the invention,

such disclosed means constituting, however, but one of various structural forms in which the principle of the invention may be used.

In said annexed drawing:

5 Figure 1 is a view, partly in elevation and partly in section, showing an anti-skid device embodying the principles of the invention, as seen in elevation placed over a tire seen partly in section;

10 Figure 2 is a side elevation of the structure shown in Figure 1, as viewed from the plane indicated by the line 2-2, seen in Figure 1, and showing the fixed end of the securing strap;

15 Figure 3 is a view similar to Figure 2, as viewed from a plane indicated by the line 3-3, shown in

15 Figure 1, showing the free end of the securing strap and the clamping device therefor;

20 Figure 4 is an enlarged fragmentary view, partly in section, taken along the line 4-4, shown in Figure 2, looking in the direction of the arrows, and showing the details of securing the fixed end of the strap;

25 Figure 5 is an enlarged fragmentary view, partly in section, taken along the line 5-5, shown in Figure 3, looking in the direction of the arrows, and showing the free end of the strap and the clamping device therefor; and

30 Figure 6 is a view similar to Figure 3, but showing a modified form of supporting plate embodying the principles of the invention.

35 As will clearly appear from Figures 1 to 3 of the drawing, the anti-skid device 1 is applied about the outer portion of a tire 2 with a securing member in the form of a strap 3 engaged beneath the wheel rim and felloe 4 intermediate 40 the spokes 5. The anti-skid device may take various forms, but preferably comprises a pair of plates 6, 7, having apertures 8 adjacent the ends thereof through which are engaged the terminal links 9 of respective pairs of cross chains 11. In 45 each of the plates the inner upper margin of the plate adjacent the apertures 8 is struck upwardly to provide a securing loop or eye 12 over which the inwardly bent ends 13 of the terminal links 9 are engaged in a manner to have free pivotal movement and be held out of direct contact with the adjacent side wall of the tire.

50 Each of the plates is made of a length to space the cross chains a suitable distance apart over the tire tread, which may be any desired distance, but, as shown, is approximately four inches between centers of the cross chain when at the central point of the upstanding loops.

55 The plates, as has been indicated, are intended to bear against the side walls of the tire on opposite sides thereof at a point beneath the point of greatest transverse diameter of the tire so as to have extended area of frictional contact with said side walls over substantially the entire inner area of the main body portion of such plates. This 60 frictional effect is enhanced by offsetting the loops for the terminal links of the cross chains in an outward direction and is further assisted by displacing the bearing member 14 for the fixed end of the strap outwardly. This bearing member is formed by striking in an outward direction a section of metal 15 from the central body portion of the plate, leaving an aperture 16 centrally of the plate, and striking a like section of metal 17 outwardly from the outer edge of the plate, 65 such section of metal 17 preferably being in the form of an extension at the lower edge of the plate so as to leave the body of the plate of approximately uniform contour at its lower edge. The displaced portions of the plate which form 70 the bearing member thus are of somewhat tubu-

lar form so as to provide a substantially cylindrical bearing member for the inner end of the strap, one end of which is engaged through the aperture to form a loop 18 around the substantially tubular bearing member 14. The end of the strap 3 just referred to is secured to the body portion thereof adjacent the bearing member by means of rivets 19 or like fastening devices. Thus the inner face of the plate 6 will be wholly free of projections of the parts attached thereto comprising the terminal links 9 and the strap loop 18, and the inner face may bear in direct frictional contact with the adjacent wall of the tire below the point of greatest transverse diameter of the tire.

5 The plate 1 for engaging the opposite ends of the cross chains 11 is provided with loops 21 outwardly offset in the same manner as the loops 12, and said loops are engaged by the inwardly turned ends 13 of the terminal links 9 in like manner. The lower portion of the plate 1 is formed with a central extension 22 in the plane of the main body portion of said plate, but with lateral extensions 23, 24, which are bent upwardly on the outer face of the structure so as to form side members of a channel of which the extension 22 is the bottom. Each of the side members is formed adjacent the inner portions thereof with apertures to provide bearings for a pin or bar 25 to the projecting ends of which a latch frame 26 of U-shaped formation is engaged through apertures formed in the free ends of such latch frame and the upsetting of the ends of the pin or bar 25 is outwardly of said terminal members in the latch frame. The latch frame is movable pivotally about the pin 25 and is provided in its side members at a point slightly above the upper margins of the side plates 23, 24, with apertures within which are engaged pivot extensions 27, 28, formed at the lower outer edge of a slidably clamping member 29 which is of inverted U-shape and of a width to have free movement between the side plates 23, 24. The opposite lower edge of the U-shaped clamping member 29 is provided with outwardly extended bearing members 31, 32, which are engaged through slots 33, 34, which slots are formed through the side plates 23, 24, centrally of the portions thereof beyond the position of the pin or bar 25, said slots inclining downwardly from a position adjacent the upper edge of the side plates to a position slightly below the position of the apertures for the pin 25. The slots are preferably made of a length so that as the latch frame 26 is moved away from the plate 1, it may be swung through an arc of slightly more than 90° before the bearing pins 31, 32 reach the outer ends of the inclined slots 33, 34.

60 The latch mechanism just described serves to securely hold the free end of the strap after the cross chains have been placed over the tread of the tire and the strap has been engaged beneath the felly of the wheel between the spokes thereof. The method of attaching the free end of the strap to the securing device is to insert the free end of the strap in the channel provided by the extension plate 22 intermediate the side plates 23, 24, and beneath the pin or bar 25, and then turn the free end of the strap so as to form a loop about said pin 25 and beneath the clamping plate 29, the rearward edge of which provides adequate space to slidably receive the free end of the strap as it is drawn outwardly over the body portion of the strap. The free end of the strap may be pulled to firmly draw the entire structure into tight engagement with the tire and adjacent wheel structure, and when firmly seated in posi-

tion is held against displacement by throwing forward the latch frame which moves the inverted U-shaped clamping member 29 downwardly in a direction defined by the angle of the slots 5 at its rearward edge and downwardly upon an arcuate path of movement at its forward edge until the further movement of the latch frame is prevented by contact with the outer face of the plate 7. When the latch frame reaches the 10 last-named position, the bearing members at the forward edge of the same will have passed slightly beyond dead center with reference to the supporting pin 25 and thus the latch plate will be automatically held against displacement. 15 Through the looping of the free end of the strap about the pin and firmly clamping the free portion of the strap against the adjacent body portion thereof, the strap is firmly held against movement, inasmuch as any tendency of the body 20 portion of the strap to move outwardly tends to move the bearing members 31, 32, downwardly in their slots into tightly clamping engagement with the pin 25 and the bottom wall 22 of the clamping device.

25 It will be noted that the inner faces of the plates 6 and 7 are free of any projecting elements and have contact with the outer wall of the tire over a large portion of their inner surface. In cases where the device is applied to a tire of unusual size the plates 6 and 7 will in any event 30 at the upper edges engage firmly against the outer tire walls at a point below the point of greatest diameter of the tire, and any tendency of the device to movement around the tire because of the greater weight of the plate having 35 the latch mechanism from the weight of the plate affording the point of attachment for the fixed end of the strap, will be counteracted by the fact that the plates cannot ride over the outwardly 40 bulged central portion of the side wall of the tire because of the greater diameter of the same. The lower edge of the plate 6 will also provide means to prevent the heavier latch member being caused to travel transversely of the tire, since such lower 45 edge will abut the rim and resist movement inwardly transversely of the tire, by the anti-skid device.

50 In Figure 6 is shown a structure substantially similar to that shown in Figure 3, but with the plate 41 formed with an arcuate upper edge and preferably also formed with a body portion 42 of dished contour so as to conform on its inner face to the contour of the adjacent outer wall of the tire. The companion plate carrying the fixed 55 end of the strap will have a corresponding shape to that of the plate 41, but will embody the features shown in Figures 2 and 4 rather than the features shown in Figures 3 and 5, as will be obvious.

60 While the cross chains are shown as conventional metal cross chains with twisted links, it is to be understood that other devices with suitable anti-skid properties may be utilized in place of the cross chains shown, and that the number 65 of such anti-skid elements may be varied with the need of the use to which the particular device is to be put.

65 Other modes of applying the principle of my invention may be employed instead of those explained, change being made as regards the structure herein disclosed, provided the means stated by any of the following claims or the equivalent of such stated means be employed.

70 I therefore particularly point out and distinctly claim as my invention:

1. An anti-skid device having in combination a pair of stamped metal plates adapted to be positioned substantially parallel to each other on the opposite outer side walls of a tire with their inner faces in direct frictional contact with said tire walls inwardly of the point of greatest transverse diameter of the tire, a securing member 5 connected with one of the plates adjacent the inner central portion thereof, a fastening element for the free end of said securing member 10 provided adjacent the inner central portion of the other of said plates, and anti-skid means extending over the tire tread and connected with the ends of said respective plates, the connections with said respective plates being offset outwardly of the plane of the inner faces of said respective plates and out of contact with the adjacent tire walls. 15

2. An anti-skid device having in combination a pair of stamped metal plates adapted to be positioned substantially parallel to each other on the opposite outer side walls of a tire with their top edges in direct frictional contact with said tire walls inwardly of the point of greatest transverse diameter of the tire, a securing member 20 connected with one of the plates adjacent the inner central portion thereof, a fastening element for the free end of said securing member 25 provided adjacent the inner central portion of the other of said plates, and anti-skid means extending over the tire tread and connected with the ends of said respective plates, said last-named connections with said respective plates being offset outwardly of the plane of the inner faces of 30 said respective plates and out of contact with the adjacent tire walls. 35

3. An anti-skid device having in combination a pair of stamped metal plates adapted to be positioned substantially parallel to each other on the opposite outer side walls of a tire with their inner faces in direct frictional contact with said tire walls inwardly of the point of greatest transverse diameter of the tire, a strap connected with 40 one of the plates at the central inner margin thereof, a fastening element for the free end of said strap provided centrally of the inner margin 45 of the other of said plates, and cross chains connected with the ends of said respective plates, all of the connections with said respective plates being offset outwardly of the plane of the inner faces of said respective plates and out of contact 50 with the adjacent tire walls.

4. An anti-skid device having in combination a pair of stamped metal plates of arcuate shape adapted to be positioned substantially parallel to each other on the opposite outer side walls of a tire with their inner faces in direct frictional contact with said tire walls along segmental areas 55 thereof inwardly of the point of greatest transverse diameter of the tire, a strap connected with one of the plates at the central inner margin thereof, a fastening element for the free end of said strap provided centrally of the inner margin 60 of the other of said plates, and cross chains connected with the ends of said respective plates, all of the connections with said respective plates being offset outwardly of the plane of the inner 65 faces of said respective plates and out of contact with the adjacent tire walls.

5. An anti-skid device having in combination 70 a pair of stamped metal plates of arcuate dished shape adapted to be positioned substantially parallel to each other on the opposite outer side walls of a tire with their inner faces in direct frictional contact with said tire walls along seg- 75

mental areas thereof over substantially the full body portion of said plates inwardly of the point of greatest transverse diameter of the tire, a strap connected with one of the plates at the central inner portion thereof, a fastening element for the free end of said strap provided centrally of the inner portion of the other of said plates, and cross chains connected with the ends of said respective plates, all of the connections with said respective plates being offset outwardly of the plane of the inner faces of said respective plates and out of contact with the adjacent tire walls.

6. An anti-skid device having in combination a pair of stamped metal plates adapted to be positioned substantially parallel to each other on the opposite outer side walls of a tire with their top edges in direct frictional contact with said tire walls inwardly of the point of greatest transverse diameter of the tire, a strap connected with one of the plates at the central inner portion thereof, a fastening element for the free end of said strap provided centrally of the inner portion of the other of said plates, and cross chains connected with the ends of said respective plates, said last-named connections with said respective plates being offset outwardly of the plane of the inner faces of said respective plates and out of contact with the adjacent tire walls.

7. An anti-skid device having in combination a pair of stamped metal plates of arcuate shape adapted to be positioned substantially parallel to each other on the opposite outer side walls of a tire with their top edges in direct frictional contact with said tire walls inwardly of the point of greatest transverse diameter of the tire, a strap connected with one of the plates at the central inner portion thereof, a fastening element for the free end of said strap provided centrally of the inner portion of the other of said plates, and cross chains connected with the ends of said respective plates, said last-named connections with said respective plates being offset outwardly of the plane of the inner faces of said respective plates and out of contact with the adjacent tire walls.

8. An anti-skid device having in combination a pair of stamped metal plates adapted to be positioned on opposite sides of a tire below the point of greatest transverse diameter with their inner faces with portions thereof in direct frictional engagement with the tire walls, anti-skid means engaged with outwardly offset elements on said plates and connecting each of said plates over the tread portion of the tire, and detachable securing means connecting said plates beneath said tire.

9. An anti-skid device comprising two long, flat, parallel plates, two chains extending between corresponding ends of the plates, each plate having at its inner edge two upwardly bowed bar elements one of which is located near each end, the main portions of said bar elements lying a considerable distance above the plane of the top of the plate to bring the under sides thereof considerably farther away from the plane of the bottom face of the plate than the thickness of the plate, hook devices on said chains passing underneath said bar elements and across the tops thereof, whereby no part of the fastenings between the chains and the plates projects below the planes of the bottom faces of the plates, each plate having a third bar element at about the middle of its long outer edge, and a tie member adapted to extend under the rim of a wheel attached to the last-mentioned bar elements; the construction being such that the plates form inward projections on the structure encircling a wheel rim and tire.

10. A side plate for an anti-skid device providing a support for the respective ends of a pair of cross chains extending over a tire tread and supported at their opposite ends by another support, comprising a long, flat, plate having at its inner edge two upwardly bowed bar elements one of which is located near each end, the main portions of said bar elements lying a considerable distance above the plane of the top of the plate to bring the undersides thereof considerably farther away from the plane of the bottom face of the plate than the thickness of the plate to permit hook devices on the chains to pass underneath said bar elements and across the tops thereof, whereby no part of the fastenings between the chains and the plate projects below the plane of the bottom face of the plate, said plate having a third upwardly bowed bar element at about the middle of its long outer edge, and a tie member adapted to extend under the rim of a wheel attached to the last mentioned bar element; the construction being such that the plate forms inward projections on the structure encircling a wheel rim and tire.

11. A side plate for emergency chain constructions comprising an elongated flat metal plate of generally arcuate shape conforming to the wheel rim curvature as seen from above, with portions displaced from the plane of the body of said plate as seen from the side edges, to provide attaching means for cross chains, and connecting elements attached to said displaced portions outwardly of the tire for securing the associated parts to a wheel.

LE ROY I. DICK.
